200,170

LINK CHAIN

Max Hartmann, Warwick, R.I., assignor to Armbrust
Chain Company, Providence, R.I., a corporation of Rhode Island

Filed May 27, 1963, Ser. No. 75,066

Term of patent 14 years

(Cl. D45—4)

FIG. 1

FIG. 2

FIG. 4

FIG. 3

FIG. 5

FIG. 1 is a front elevational view of a link chain showing my new design;

FIG. 2 is a top edge view thereof;

FIG. 3 is an enlarged front elevational view of one of the links per se;

FIG. 4 is a top edge view thereof; and

FIG. 5 is an end view thereof, looking from the right at the link illustrated in FIG. 4.

Portions of the link chain are shown broken away to denote indeterminate length.

I claim:

The ornamental design for a link chain, substantially as shown and described.
